(57) **CLAIM**

The ornamental design for a shell of an electronic device as shown and described.

DESCRIPTION

FIG. 1 is a top front perspective view of a shell of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Dot-dash broken lines seen in the drawings represent the boundary of the claimed portion and the unclaimed portion and form no part of the claimed design. All other broken lines depict portions of the shell of an electronic device which form no part of the claimed design. Unshaded surfaces enclosed with boundary lines form no part of the claimed design. Unshaded surfaces shown between solid and broken lines form no part of the claimed design. Surfaces defined by both solid and boundary lines are included in the claim.
